UNITED STATES PATENT OFFICE.

EDWARD J. BROOKS, OF EAST ORANGE, NEW JERSEY, ASSIGNOR TO E. J. BROOKS & CO., OF NEW YORK, N. Y.

INKING-PAD.

SPECIFICATION forming part of Letters Patent No. 447,714, dated March 3, 1891.

Application filed December 4, 1890. Serial No. 373,556. (No model.)

To all whom it may concern:

Be it known that I, EDWARD J. BROOKS, a citizen of the United States, and a resident of East Orange, in the State of New Jersey, have 5 invented a new and useful Improvement in Inking-Pads, of which the following is a specification.

This invention is additional to my improvement in inking-pads patented October 14, 10, 1890, by Letters Patent No. 438,571, as claimed in the second claim of my specification forming part of the same.

The present invention consists in certain novel combinations of peculiarly-formed or 15 peculiarly-arranged parts, as hereinafter set forth and claimed; and its objects are to securely attach the felt top of the pad at all points, so that it shall not rise with the stamp and thus become stretched or uneven, and to 20 protect the preferred cork composition or any other like composition of which the relatively inflexible elastic support is composed against exposure to the air, which in practice is found to render the same liable to mold and disintegrate. These beneficial results have been 25 accomplished without materially increasing the cost of the pads.

A sheet of drawings accompanies this specification as part thereof.

30 Figure 1 of the drawings is a perspective view of a round pad illustrating this invention. Fig. 2 is a like view of its relatively-inflexible support. Fig. 3 is a perspective view of a square pad of like construction. 35 Fig. 4 represents an enlarged section on the line 4-4, Fig. 1, and Fig. 5 is a like sectional view of a modified pad constructed according to the same invention in part.

Like letters of reference indicate corresponding parts in the several figures.

The improved pad may be round or square, as illustrated by the drawings, or of any preferred external shape. In all forms it is preferably constructed with the customary bevelled edges, as shown, so that its bottom and top are of equal area, and the ink-absorbing felt A or A² or A' is surrounded by the customary lip a of the roller composition or gelatine compound, of which the base of the pad 45 is mainly composed. The relatively inflexible elastic support B B' is now preferably molded of a form corresponding with that of

the base of the pad, as represented by Fig. 2, and in the species represented by Figs. 1, 2, and 4 is provided with a sufficient number of holes 55 h, Fig. 2, penetrated by binding portions b, Fig. 4, of the gelatine compound C, which encloses the support B and completes the base of the pad. The gelatine-compound portion CC' C' of each of the pads further comprises a 60 distinct and substantial elastic binding-layer c, Figs. 4 and 5, extending under the whole area of the felt A A' A' as an adhesive support for the same at all points, the same serving also, in connection with a relatively inflexible support, as B, of the preferred cork composition, composed of particles of cork embedded in gelatine compound to protect the latter against access of air, and thus to keep it from molding, as aforesaid. The top of the pad is also 65 rendered softer without impairing the effect of the relatively inflexible support. In connection with said layer c c of the gelatine compound, a relatively inflexible support B', of cork composition or the like, without said holes 70 h, may in some cases be employed, as illustrated by Fig. 5, and such relatively inflexible support may be made with any suitable sawdust in place of cork particles, or in the perforated form B of sheet-cork, or of suitable 75 wood without wholly departing from my invention.

A paper label D, Fig. 5, may be adhesively attached to the bottom of the pad.

In producing the improved pad within a 80 suitable mold in inverted position, as before, a sufficient quantity of the gelatine compound is poured upon the felt to form the lip a and binding-layer c c. The relatively inflexible support B, rendered adhesive by heating it, 85 is then placed upon said layer c c, and sufficient of the gelatine compound is added to complete the base of the pad.

Having thus described said improved pads, I claim as my invention, and desire to patent 90 under this specification—

1. An inking-pad having an ink-absorbing top of felt, an elastic cushioning and binding portion of gelatine compound or the like, comprising a layer c c of the same immediately 95 beneath the felt, and a relatively inflexible elastic support composed of particles of cork or the like embedded in gelatine compound, which immediately underlies said layer c c 100

and is inclosed within the gelatine compound, which completes the base of the pad, substantially as hereinbefore specified.

2. In an inking-pad having an ink-absorbing top of felt and an elastic cushioning and binding portion of gelatine compound or the like, a relatively inflexible support B, provided with holes h , penetrated by binding

portions of the gelatine compound, which incloses said relatively inelastic support and completes the base of the pad, substantially as hereinbefore specified.

EDWARD J. BROOKS.
